UNITED STATES PATENT OFFICE.

RICHARD V. ELSEY AND EDWARD T. LADD, OF MARIONVILLE, MISSOURI.

CLEANER FOR GASOLINE-MEASURING TANKS.

Application filed March 26, 1925. Serial No. 18,652.

This invention relates to cleaners for the glass bowls of visible gasoline tops.

The object of the invention is to provide a cleaning device of this character which operates similar to the ram rod of a gun being constructed to clean the interior surface of the bowl on the raising and lowering of the overflow pipe forming a part of the gasoline dispensing stand.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a front elevation of a visible gasoline top equipped with this invention;

Fig. 2 is a top plan view of one form of the invention;

Fig. 3 is a longitudinal section taken on line 3—3 of Figure 2;

Fig. 4 is a plan view of another form of the invention; and

Fig. 5 is a transverse section thereof.

In the form shown in Figs. 1 to 3 a gasoline dispensing stand 1 is shown having the usual supporting frame 2 for a glass gasoline container or measuring tank 3 in which is located the overflow pipe 4 which is raised and lowered by a crank handle 5. The discharge pipe 6 such as is usually employed in tanks of this character is shown in Fig. 1.

The cleaner 10 as shown in Figs. 1 to 3 comprises a metal ring 11 made channel-shaped in cross section with the channel opening outwardly to receive and form a seat for the cleaning element 12 which is shown as composed of a felt strip but obviously may be composed of any suitable material. This cleaner 12 projects beyond the outer face of the ring 11 as shown clearly in Fig. 3 so that when the ring is moved up and down in the tank 3 this element 12 will engage the interior of said tank and operate to clean the walls thereof.

The channel-shaped ring 11 is mounted on the upper end of a cap 13 which is designed to be screwed on the top of the overflow pipe 4, said cap being provided with a plurality of apertures 14 to provide for the overflow of the gasoline. A cross bar 15 connects the ring 11 with the cap 13 and as shown is composed of three sections 16, 17 and 18 bolted to each other and to the ring, the sections 16 and 18 having right angular arms 19 which are engaged with the inner faces of the ring and bolted thereto as is shown clearly in Fig. 3. The section 17 passes through diametrically opposite apertures 14 in the cap 13 and is bolted to the top of the cap as shown in Fig. 3. The ends of this section 17 project beyond the cap and underlie the meeting ends of the sections 16 and 18 so that when connected the upper faces of the sections 16 and 18 will be flush with the outer face of cap 13.

The ring 11 is shown made transversely split as indicated at 20 but obviously it need not be split as it can be made in one piece if desired. These rings are made of various sizes to fit various sized tanks or bowls 3, the cleaning element 12 may be either in the form of felt, bristles or any other material.

By connecting this cleaner 10 with the overflow pipe, the inner surface of the tank 3 is automatically cleaned as the overflow pipe 4 is moved within the tank 3 in dispensing gasoline from the tank.

In the form shown in Figs. 4 and 5 an annular float 21 is shown which is designed to rest on top of the gasoline in tank 3 and rise and fall therewith. This float 21 is provided with peripherally arranged brushes 22, or with other suitable cleaning means, which are designed to engage the side walls of the bowl on the rising and falling of the gasoline in the tank.

It is of course understood that the float 21 must be made of light material such as copper, aluminum or tin, to provide for its rising and falling with the liquid.

We claim:—

In combination with the vertically movable overflow pipe of a gasoline measuring receptacle, a cleaner embodying a circular

member, a cleaning member secured to the periphery of the circular member, a cap secured to the circular member and adapted to be positioned on the upper end of the overflow pipe, said cap having openings adjacent to the circular member to permit fluid to pass therethrough and into the cap and overflow pipe, and said cleaner adapted to

engage the inner surface of the measuring receptacle to clean the surface.

In testimony that we claim the foregoing as our own, we have hereunto affixed our signatures.

RICHARD V. ELSEY.
EDWARD T. LADD.
